UNITED STATES PATENT OFFICE.

EDWARD F. MEEHAN, OF FORT WADSWORTH, NEW YORK.

SURGICAL BANDAGE.

1,319,299.

Specification of Letters Patent.

Patented Oct. 21, 1919.

Application filed April 30, 1918. Serial No. 231,736.

To all whom it may concern:

Be it known that I, EDWARD F. MEEHAN, a citizen of the United States, residing at Fort Wadsworth, in the county of Rich-
mond, State of New York, have invented
certain new and useful Improvements in
Surgical Bandages; and I do hereby declare
the following to be a full, clear, and exact
description of the invention, such as will
enable others skilled in the art to which it
appertains to make and use the same.

This invention is an improvement in surgical appliances and has particular reference to a bandage.

An object of the invention is to provide an improved bandage adapted to be applied to a wound in such manner as to effectively protect the same and prevent further injury to and also permit of proper ventilation of the wound while healing.

Another object is to provide a bandage of this character which is simple in construction, easy to manufacture and effective in carrying out the purpose for which it is designed.

The inventive idea involved is capable of receiving a variety of mechanical expressions one of which, for the purpose of illustrating the invention, is shown in the accompanying drawing wherein:

Figure 1 is a plan view of one side of the bandage.

Fig. 2 is a similar view of the other side.

Fig. 3 is a transverse section through the bandage.

Fig. 4 is a perspective view of the plate or body portion of the bandage.

The bandage is illustrated in what is now believed to be its preferred form and comprises a plate or body portion 5 of disk-like formation and made of steel or other light material which is nickel plated to prevent rusting, the plate being formed from a relatively thin sheet of material so that the same may be flexed as desired. The plate 5 is preferably concaved or bent so that the central portion thereof will be spaced from the wound over which the plate is placed and said central portion is provided with a plurality of ventilating openings 6 which will permit the air to pass through the plate and thus aid in healing the wound.

A casing for the plate 5 is provided and this casing preferably comprises a pair of covers 7 and 8 made of relatively thin and

soft leather and having their outer edges extending beyond the edge of the plate 5 in abutting relation and stitched or otherwise secured together as indicated at 9 and 10 to form a rim portion. The cover 7 engages the outer surface of the plate 5 and entirely covers the same with the exception of the central portion thereof which is provided with the openings 6 and at this point the cover has an opening 11. The cover 8 completes the inclosure of the plate and extends into the concaved inner face thereof and is provided centrally with an opening 12 which registers with the opening 11. The central portion of the covers 7 and 8 are secured together by stitching 13 which passes through certain of the openings 6 in the plate 5.

In order to further protect the wound, a layer of cotton or other absorbent material 14 is preferably interposed between the inner cover 8 and the adjacent inner surface of the plate 5 and is held in this position by the stitchings 10 and 13 so that the layer of cotton will be held properly to form a pad. It will be noted that when so mounted the layer of cotton 11 may be readily replaced after first removing the stitchings 9 and 10.

For the purpose of securing the bandage to the body, the covering is provided with buckles 15 secured thereto and adapted to be engaged by oppositely disposed straps 16 which are passed around that portion of the body to which the bandage is applied and secured so as to prevent detachment thereof.

It will be noted that the cover members 7 and 8 extend beyond the periphery of the curved plate 5 so that the filling 14 is between the edge of the plate and the cover member 8. There is thus provided a yielding padding between the edge of the plate and the cover member with its obvious advantage. It will also be noted that the stitched portions of the cover members are so positioned that the padded portion of the casing bears against the surface surrounding the wound.

What is claimed is:—

A surgical bandage comprising a curved plate having a plurality of openings in its central portion, a casing for the plate including a pair of covers having their outer edges and portions adjacent the outer edge of the plate secured together, and also having central openings the edges of which surround

certain of the openings in said plate, means extending through others of said openings in the plate and engaging said covers to secure the latter to the plate, and a layer of 5 absorbent material interposed between one of the covers and the adjacent face of the plate.

In testimony whereof, I affix my signature, in the presence of two witnesses.

EDWARD F. MEEHAN.

Witnesses:

JOHN J. BARRY,
JOHN G. SAVARESE.
